UNITED STATES PATENT OFFICE.

CHARLES M. RUSSELL, OF BOWLING GREEN, KENTUCKY, ASSIGNOR OF ONE-THIRD TO THOMAS B. LYNE, OF SAME PLACE.

TELEGRAPH-POLE.

SPECIFICATION forming part of Letters Patent No. 406,406, dated July 2, 1889.

Application filed October 8, 1888. Serial No. 287,544. (No model.)

To all whom it may concern:

Be it known that I, CHARLES M. RUSSELL, a citizen of the United States, residing at Bowling Green, in the county of Warren and 5 State of Kentucky, have invented certain new and useful Improvements in Telegraph-Poles; and I do hereby declare the following to be a full, clear, and exact description of the invention, such as will enable others skilled in the 10 art to which it appertains to make and use the same.

This invention relates to improvements in telegraph-poles and insulators therefor, the object of the invention being to provide a 15 skeleton telegraph-pole which shall be strong, durable, and ornamental, and which shall be light, portable, impervious to moisture, and practically fire-proof; also to combine with said telegraph-poles insulators of such construction that they may be placed upon the wires so as to incase them and be secured to the cross-pieces of the pole without the use of the usual dowel-pins, as hereinafter fully set forth.

25 With these objects in view my invention consists in the special construction, combination, and arrangement of the several parts of the telegraph-pole, substantially as herein-after described, and set forth in the claim.

30 Figure 1 represents in front elevation a metallic telegraph-pole constructed in accordance with my invention; Fig. 2, a sectional detail of the post on dotted line xx , Fig. 1, showing one of the triangular spiders or brackets 35 through which the standards of the pole extend; and Fig. 3, an enlarged detail showing the manner in which the cross-piece is secured to the standards of the telegraph-pole, the cross-piece being shown in section; and 40 Fig. 4 represents in elevation a modified construction of base to be driven into the ground to support the standards.

In the drawings, A B C represent three 45 supporting-standards constructed, preferably, of piping or tubes, and arranged in the shape of a tripod, the upper ends coming into close proximity and gradually diverging from this point to the lower ends, the magnitude of divergence depending upon the height of the 50 pole, and which will be determined by the re-

quirements. These standards are secured together by a series of brackets or spiders D, which will preferably be made of cast-iron, the standards being extended through vertical holes in the arms of said brackets, said brackets being of different sizes, with the standard-holes different distances apart to correspond to the area of the tripod at the place where the brackets are to be secured. The upper bracket will be held in place upon the rods, 60 preferably by nuts a' , as shown in Fig. 1, while the lower one will rest upon (preferably) a foundation-stone b , the standards being extended entirely through said stone and held by nuts. The intermediate brackets 65 will be slipped on the standards from the top before the top standard is secured thereto and forced downward until they bind, where they may be keyed, if desired. It is preferable to use piping for the standards, as rigidity is secured with lightness of construction. It is obvious, however, that angle bars or rods might be used instead of the pipes without departing from my invention.

The cross-pieces E, which may be constructed of wood or metal in the usual form, are secured to the upper ends of two of the standards A B by eyebolts or staples c , which encircle the standards and extend through the cross-pieces, where they are secured by 80 nuts c' , the incline of the standards and position of the eyebolts preventing the cross-pieces from slipping down. Each of the cross-pieces E has a series of transverse horizontal holes d' cut through it, with a transverse notch d^2 , cut from the upper edge and communicating with the hole d' .

The glass insulators F, which encircle the wires F', are inserted into the holes d' in the cross-pieces, said insulators being constructed 85 in two halves. By this construction the cross-pieces may be placed with their upper and lower edges in contact with the lower and upper edges of the next adjacent cross-piece, thus greatly economizing in space, as the space 90 usually occupied by the upwardly-projecting dowel-pins and insulators in common use can be utilized.

Inasmuch as the special construction and arrangement of insulator and cross-bar may 100

contain patentable novelty, they will form the subject-matter of a separate application.

If desired, the lower bracket may be firmly secured to the lower ends of the standards by 5 nuts or otherwise, with the ends of the bolts extending a considerable distance below, so as to be buried in the ground, in which case the foundation-stone will be dispensed with, or the standards may have a pointed base, 10 each to be driven into the ground, said base having longitudinal tapering radial ribs, as shown in Fig. 4.

I claim—

15 In a telegraph-pole, the combination of the tubular standards A B C, arranged in the shape of a tripod, the cast-metal brackets or spiders having the vertical holes, through

which the standards are extended, the cross-pieces E, having transverse horizontal holes therein to receive the insulators, the staples 20 e, extending through the cross-pieces and around the standards, where they are secured by bolts, and the insulators seated in the holes in the cross-pieces, so as to not project above or below said cross-pieces, whereby 25 the cross-pieces may be secured to the standard in close proximity to each other, substantially as described.

In testimony whereof I affix my signature in presence of two witnesses.

CHARLES M. RUSSELL.
